UNITED STATES PATENT OFFICE.

WILLIAM HURST, OF WINNIPEG, MANITOBA, CANADA.

ELECTRICAL WATER HEATER.

Application filed December 23, 1919. Serial No. 346,855.

To all whom it may concern:

Be it known that I, WILLIAM HURST, of the city of Winnipeg, in the Province of Manitoba, Canada, have invented certain

5 new and useful Improvements in Electrical Water Heaters, of which the following is the specification.

The invention relates to improvements in electrical water heaters, particularly as 10 utilized to heat the water of the water cooling system of combustion engines and the principal object of the invention is to provide an electrical heating attachment readily insertable in the water cooling system and 15 which when connected electrically with a suitable source of electro-motive force will heat the water sufficiently to establish a circulation and prevent the same from congealing or freezing.

20 A further and important object of the invention is to construct a heater such that the heating element thereof will not obstruct to any extent the flow of the cooling waters and which is arranged so that it can be attached as a unit in the water cooling system.

A still further object of the invention is to construct the heater with an offset permitting of the easy insertion of the heating element, the element being inserted at 30 the offset.

A still further object of the invention is to provide a special coupling for attaching the heating element to the casing.

A still further object of the invention 35 is to arrange the coupling in a manner such that should there be no water in the casing there will be a natural tendency under the excessive heat developed for the coupling to come undone.

40 With the above more important objects in view the invention consists essentially in the arrangement and construction of parts hereinafter more particularly described and later pointed out in the appended claims, reference being had to the accompanying drawing in which:

Fig. 1 is a side view of my heater applied in the water circulating system of an automobile engine.

50 Fig. 2 is a perspective view of the heater detached.

Fig. 3 is a perspective view of the electrical heating element.

55 Fig. 4 is a perspective view of the bushing or coupling nut.

Fig. 5 is a horizontal longitudinal sectional view through the heater.

Fig. 6 is an enlarged detailed sectional view at 6—6' Fig. 5.

In the drawing like characters of reference indicate corresponding parts in the several figures.

1 represents an internal combustion engine such as an automobile engine and 2 an automobile radiator. 3 is the outlet water manifold or pipe leading from the water jackets of the engine cylinders to the top of the radiator and 4 represents the customary outlet pipe opening to the bottom of the radiator and connected through a hose 65 connection and my heater with the water inlet manifold 5 of the engine.

The above parts are of ordinary construction and for this reason are not herein further described.

75 The heater which I provide comprises three essential elements, a casing 6, an electrical heating element 7 and a coupling 8 connecting the element to the casing. The casing is in the nature of a pipe 9 provided at one end with an outstanding circumscribing rib 10 and at the other end in an elbow 11 terminating in a flanged head 12.

Intermediately of its length the pipe is formed with an offset 13 which provides a 85 receiving chamber for the electrical heating element, the offset being in direct communication with the pipe. One end of the offset is faced as indicated at 14 and is interiorly screw threaded as indicated at 15 90 to receive a bushing or coupling nut 16.

The electric heating element 7, which I employ presents the following parts:

The heater 7 comprises a closed cylinder 17 containing a resistance coil 18 wound on 95 a porcelain or such like body and insulated by an enclosing mica or such like covering 19. 20 is a tubular neck extending from one end of the cylinder and terminating in a flaring cup 21 which contains a pair of 100 contact tips 22 and 23 in direct electrical connection through the neck with the resistance coil.

105 The bushing or coupling 16 whilst screw threading into the threaded opening 15 is designed also to permanently carry the electrical heating element which is passed through it.

In the present instance, the bushing is fitted with a central opening 24 of a di- 110

2
ameter slightly larger than the diameter of the cylinder 17 so that when assembling one simply passes the bushing over the cylinder to take a place on the neck as best shown 5 in Fig. 5. After having passed the bushing to this position I fasten it permanently to the neck as by soldering as indicated at 25, the solder filling in the whole space between the bushing and the contracted 10 neck.

By making this special coupling it will be apparent that I can pass the cylinder 17 through the coupling 16 and afterwards solder the coupling to the neck.

15. The assembled heater is attached to the water inlet manifold of the engine by bolting the flange 12 to the manifold as shown at 26 and if reference be made to Fig. 1 it will be apparent that the heater takes a 20 slightly inclined position with the offset 13 towards the engine which is a desirable place as one obtains the benefit of the heat radiated from the engine.

The lower end of the heater is connected 25 to the pipe 4 by a hose connection 27.

In actual practice one connects the heaters to a suitable source of electro-motive force by inserting the common type of well known push plug into the cup or socket 21, the push 30 plug making contact with the tips 22 and 23 and being in electrical connection through suitable wires with the source of electrical energy.

When the heater is in operation the water 35 in which the cylinder 17 is immersed becomes heated and in so doing establishes a circulation through the water system of the cylinders, thereby preventing the water from freezing.

40. This device is of course particularly adapted for attachment to the water cooling system of an engine which is operating in cold climates and where low temperatures require the water to be kept heated to avoid 45 freezing when the engine is not running.

I have found by actual demonstration that in instances where there is no water in the 50 cooling system such as some times occurs my heater works automatically to short circuit the feed wires and blow out the fuse customarily employed in such electrical circuits. This occurs in the following way:—

Due to the absence of water the heater and parts containing the same become intensely hot and the heat developed melts the 55 solder which allows the heating element 7 to drop and contact with the wall of the casing. After a short time the metal of the cylinder 17 will actually burn out and the coil 18

will contact with the casing and as soon as 60 this occurs the fuse plug will blow out. Accordingly there is no possibility of a fire occurring as immediately the element is short circuited it becomes electrically dead.

What I claim as my invention is:—

1. The combination with the circulating water cooling system of a water jacketed engine, of an electrical water heater demountably inserted in the system at the inlet to the water jacket and having an inclined position and provided with an offset chamber 70 extending towards the engine and containing the electrical heating element.

2. In a water heater, the combination with a casing, constituting a fluid conduit, 75 of a fluid heater comprising an electrical heating element supported within the casing, a neck portion extending from said heating element outwardly through the wall of the casing, contacts carried by the outer end of 80 said neck portion electrically connected with said heating element, and means for securing and supporting the heating element within the casing comprising a coupling nut surrounding the neck portion and secured 85 thereto by a fusible binding substance, said coupling nut being threadedly engaged in the wall of the casing.

3. An electrical water heater comprising 90 an electrical heating element, a neck portion extending from said heating element, electrical contacts carried by the outer end of said neck portion and electrically connected with said heating element, and a coupling nut surrounding said neck portion and secured 95 thereto by a fusible binding substance, the bore of said coupling nut being made larger than the diameter of the heating element to permit of the passage of the latter therethrough when assembling the nut with the 100 neck.

4. A liquid heating element comprising an open ended conduit formed with a lengthwise extending offset having a transverse end wall, said end wall being formed with 105 an orifice, an electrical heater within the offset having an extremity within said orifice and engaged rigidly with said end wall, and means exterior to said offset and conduit for establishing electrical connection with said 110 heating element.

Signed at Winnipeg, this 27th day of November 1919.

WILLIAM HURST.

In the presence of—

GERALD S. ROXBURGH,
K. B. WAKEFIELD.
